UNITED STATES PATENT OFFICE.

JOHN H. SCHUSSLER, OF CHICAGO, ILLINOIS.

INKING MECHANISM FOR PRINTING PRESSES.

Application filed July 5, 1924. Serial No. 724,224.

My invention relates to inking mechanism for printing presses of the Gordon type and has for its primary object the provision of inking mechanism for printing presses of this type, which approximates the ink distribution secured upon printing presses of the flat bed type.

Another object of my invention is the provision of an inking mechanism in which the amount of ink supplied to different parts of the form may be varied. In some classes of printing work it is desirable to supply more ink to one side of the form than upon the other, and in my improved inking distributing mechanism this can be accomplished by regulating the flow of ink from the ink fountain.

Another and further object of my invention is a provision of ink mechanism which thoroughly works and distributes the ink before it is picked up by the form rolls and conveyed to the printing forms, so that the ink conveyed to the forms is thoroughly cut and as a result the forms are evenly inked resulting in a higher grade of printing.

Another and further object of my invention is the provision of an ink mechanism by means of which the rotary inking plate, commonly in use upon presses of this type, is dispensed with and I am able to secure better ink distribution than with the old rotary inking type presses.

It has long been known that a weakness exists in the use of a circular disc in printing presses of this type, because a matter in the center of the form receives better inking than matter at the end of the chase, because there is better ink distribution at the center of the circular plate than there is along the marginal edges. If the ink supply is increased to supply an adequate amount to the ends of the chase, then too much ink is applied to the center of the form, so that by the use of a stationary plate and adequate ink distributing means therefor this difficulty is overcome and better printing results. It is, of course, well known that the problem of inking form surfaces and the distribution of printer's ink is extremely difficult because of the physical properties of the ink itself, and by the use of my invention I am able to secure better ink distribution than what has been heretofore possible with printing presses of this type. The general arrangement of a similar inking mechanism is shown and described in my co-pending application Serial

No. 562,626, filed May 22, 1922, and my present invention is an improvement upon the apparatus shown and described in that application because of different arrangement of 60 rollers for ink distribution and also in operation of these rollers.

This and other objects of my invention will be more fully and better understood by reference to the accompanying sheets of drawing and in which—

Figure 1 is a plan view of my improved invention;

Figure 2 is a side elevation view, showing the ink fountain and distributing rolls; 70

Figure 3 is a side elevational view, showing the distributing and inking rolls in different position than those shown in Figure 2;

Figure 4 is a detailed side elevational view of the opposite side of press shown in Figures 75 2 and 3;

Figure 5 is a cross sectional view partially in elevation on lines 5—5 of Figure 2;

Figure 6 is a detail side elevation view of the inking fountain and distribution carriage; 80

Figure 7 is a detailed view showing one of the racks and the gear connections therefor by means of which the movement of the inking distributing carriage is limited; 85

Figure 8 is a sectional view of the roll shown in Figure 5 and is a modified form of the distributing roll shown in Figure 5;

Figure 9 is a detailed sectional view of lines 9—9 of Figure 8; 90

Figure 10 is a sectional view of a modified form of my improved invention showing the inking distributing means operated by a segmental gear instead of a rack; and,

Figure 11 is a side elevational view of the 95 modified form shown in Figure 10.

Referring now specifically to the drawing and in which like reference characters refer to like parts throughout, a printing press frame 14 is shown having supporting arm 15 attached thereto to which a stationary ink plate 16 is secured in any approved manner. A form holding rocking frame 16 is shown and which has a pair of rocker arms 17 and 18 mounted thereon, upon which the usual inking frame 19 is mounted, having form rollers 20, 20 mounted thereon which pass over the ink plate 16 and down over the form in manner common to presses of this character. Secured to the frame 14 is a pair of brackets 21 and 22 which extend upwardly under the stationary plate 16 and which have projection

portions 23 and 24 formed thereon, the upper sides of which form tracks upon which the rollers of an auxiliary inking carriage run as will be more fully described hereinafter. 5 Mounted upon the upper ends of the brackets 21 and 22 is an ink fountain 25, having a fountain roller 26 mounted therein upon a shaft 27, the roller 26 acting as a feed roll through which ink is fed from the fountain 25 onto a 10 distributing roller. Mounted upon each side of the brackets 21 and 22 is a pair of toothed racks 27 and 28, the said racks being slidably mounted in guide ways 29, 29 which are secured to the sides of the arms 21 and 22 in 15 any approved manner. At the lower end of the rack 28 is mounted a head 30 which is secured to the rack 29 by means of a pair of screws 31, and which has mounted upon it a T-shaped head 32 which is connected to the 20 head 30 by a threaded pin 33 having a nut 34 mounted thereon and by means of which the head 32 can be adjusted vertically with reference to the head 30. A pair of pins 35 and 36 with compression springs 36^a on the lower 25 ends thereof is provided with blocks 37 and 38 mounted thereon which extend through the head 30 and through the lower portion of the head 32, the blocks 37 and 38 having recesses 39 and 40 in the sides thereof within 30 which the shafts 41 and 42 of rollers 43 and 44 are carried. These blocks rest upon the T-portion of the head 30 and against the sides of the head. On the opposite side of the press is mounted a similar head 45 upon the lower end 35 of the rack 27 and which has an upper T head 46 secured thereto, within which the ends of the shafts 41 and 42 are mounted in precisely the same manner as the mounting described for the rolls 43 and 44 on the opposite side of 40 the press. Seated in recesses formed in the upper side of the heads 32 and 46 is a shaft 47 having a roller 48 mounted thereon which is seated upon and rides in peripheral contact with each of the rollers 43 and 44 and acts as 45 an ink distributing roller. It will thus be understood that the rollers 43 and 44 and their mountings upon the racks 27 and 28 form an auxiliary ink conveying and distributing means as the rollers 43 and 44 pass 50 downward over the plate 16 and act as ink conveying rollers and distributors for conveying and distributing ink on to the plate 16 as it is received from the fountain and as will be more fully hereinafter described. The shaft 55 55 has a pair of rolls 49 and 50 mounted thereon which ride upon the outer upper portions of the projections 23 and 24 and serve to raise up the roller 43 slightly as it leaves the plate 16. A pair of rollers 51 and 60 52 are mounted upon the shaft 42 and also ride upon the upper side of the projections 23 and 24 and which have slightly raised track portions 53 and 54 thereon, so that the upper roller 44 is carried above and clears an ink 65 distributing roller 55 which is mounted upon

a shaft 56 mounted in the brackets 21 and 22. The rollers 51 and 52 drop down into recesses formed in the projecting portions 23 and 24 of the brackets 21 and 22 after the upper inking roller 44 has passed over the roller 55, the 70 rollers 43 and 44 thereby contacting with the roller 55 which acts as an ink conveying and distributing roller to the auxiliary inking carriage hereinabove described. The roller 55 is loosely held upon the shaft 56 by a longitudinal key 57, and is moved longitudinally of the shaft 56 by the member 58 in threaded engagement with the roller 55, the member 58 being held against rotation by a screw 59 in the bracket 22. Mounted upon each end of the shaft 56 are gear wheels 60 and 61 respectively in toothed engagement with the racks 27 and 28 respectively and through which the racks are moved downwardly so the rollers 43 and 44 are brought into contact with the 85 surface of the inking plate 16.

Mounted in brackets 62 and 63 secured to the under side of the ink fountain 25 is a shaft 64 having a pair of upwardly extending rocker arms 65 and 66 secured thereto in the 90 upper ends of which is mounted a ductor roller 67 adapted to alternately engage in rolling peripheral contact with the fountain roller 26 and the distributing roller 55, and moved into these alternate positions by a cam 68 having a spring 69 secured to its rear end and to the fountain 25 and having a sloping forward end 70 with a straight portion 71 cooperating with a roller 72 carried by the head 45 so that as the roller 72 engages the sloping surface 70 of the cam, the roller 67 is forced upward against the roller 26 and held there against as long as the roller 67 remains in contact with the straight surface 71 and that the entire surface of the roller 67 receives a coating of 100 ink from the fountain roller 26 which is being rotated by mechanism hereinafter described. As soon as the cam 68 is released by the rollers 72 passing below the cam member 68 the spring 69 forces the roller 67 into contact with the distributing roller 55 conveying a supply of ink onto this roller which is being rotated and also moved transversely by the operation of the printing press. An auxiliary distributing roller 73 is provided 105 which rests in inclined slots 74 and 75 in the fountain 25 and which operates in rolling peripheral contact with the distributing roller 55 and assists in the cutting and distribution of ink thereon.

Mounted upon the rocker arm 17 is a clip 76 to which is secured a toothed rack 77 and which is supported at its upper end by a loop 78 secured to the shaft 27 upon which the fountain roller 26 is mounted, the said rack being in engagement with a gear wheel 79 loosely mounted upon the shaft 27 and which in turn engages a small idler 80 secured to the side of the ink fountain 25 and which in turn is in engagement with a gear wheel 81

100

105

110

115

120

125

130

mounted upon the side of the fountain 25 and which is secured to a large gear wheel 82, and which in turn engages the gear wheel 61, which engages the rack 28 and through the 5 shaft 56 and gear 60 in engagement with the rack 27 so that as the rack 77 is moved up and down by the operation of the rocker arm 17, the auxiliary inking and distributing carriage is moved backward and forward over 10 the ink plate 16 and the roller 55 is constantly kept turning except at the end of each path of movement of the rocker arm 17 so the ink applied thereto by the roller 67 is cut and evenly distributed upon its surface and conveyed 15 to the rollers 43 and 44. In the lower end of each of the racks (see Figure 7) is placed a spring pressed inclined tooth 83 mounted upon a stud 84 which yields when the gear wheel 61 is running in one direction 20 and which engages in the teeth of the wheel 61 when the direction of rotation of the wheel 61 is reversed. Similar spring teeth 85 and 86 are provided in the upper end of the racks 25 27 and 28 so the movement of the racks is limited by the length of the toothed portions thereof regardless of the distance of travel of the rack 77.

Also mounted upon the clip 76 is a rod 87 which engages an arm 88 which has a pawl 89 secured thereto, which in turn engages a ratchet wheel 90 secured to the fountain roller 26, and which has an adjusting handle 91 secured thereto by means of which the extent of rotation of the fountain roller 26 is controlled, and therefore the supply of ink carried out of the fountain by this roller. A throw off rod 92 is connected to an eccentric 93 at one of its ends and to a rotatable collar 94 at its opposite end by means of which the 40 pawl 89 is held out of engagement with the ratchet wheel 90 when the press is thrown off impression, these devices being particularly in my application Serial No. 562,626 above referred to.

Referring now specifically to Figure 11 in which a modified form of my invention is shown and in which the rack 77 is dispensed with, I provide segmental gear 95 which is mounted upon the shaft 27 and is operated by the arm 88 which also turns the fountain roller 26, the said arm 88 being connected by the rod 87 to the clip 76 as heretofore described. The segmental gear 95 engages with the idler 80 and otherwise operates in precisely the 55 same manner as heretofore described.

In Figures 8 and 9, I also show a modified form of distributing roller which may be used instead of the roller 55 heretofore described, and in which a shaft 95 is shown having a keyway 96 therein within which a key 97 seats, which is carried by the gear wheel 61. The shaft has a roller 98 mounted thereon and has a threaded portion 99 in engagement with internal threads on the bracket 21, so that 60 as mechanism is operated the roller and shaft

are moved transversely, instead of the roller being moved upon the shaft as shown in the form illustrated in Figure 5.

From the foregoing description, operation of the device will be readily apparent to those skilled in the art, and it will be understood that a supply of ink is placed in the fountain 25 and as the press operates the rocker arm 17 which has the form inking rolls mounted upon one end thereof oscillates 70 and moves the rack 77 up and down which through the chain of gears heretofore described keeps the distributing roller 55 constantly in motion except at the instant of reversal of movement of this roller, the 75 movement of this roller being reversed with each movement of the rocker arm 17, and also causing the roller 55 to travel transversely to the shaft 66 so that effectual ink distribution is had while the rollers 43 and 44 are in 80 contact with this roller. When these rolls are pushed downward over the plate 16 by the operation of the rack, the roller 67 is brought into contact with the distributing 85 roll 55 and the supplying ink conveyed thereto and as these rolls return the roller 67 is moved backward against the fountain roll 26 which is being rotated at this stage of the 90 operation by the arm 88, so that a supply of ink is given to this roller and by the form of the cam surface 71 on the cam member 68, this roller is caused to remain in contact with the fountain roller 26 so that it is rotated perhaps two or three times before being rocked across into contact with the 95 roller 55. This operation continues and as heretofore described, if the press is thrown off impression the pawl 89 is kept out of engagement with the ratchet wheel 90 while the press is off impression, so that the fountain 100 and roller 26 is not rotated and therefore no ink is conveyed to the surface of the roller 67. It will thus be understood that a complete cutting and distributing of the ink is effected through the operation of 105 the various rolls which is comparable through the ink distribution secured with a flat bed press.

While I have described more or less precisely the details of construction, I do not wish to be understood as limiting myself thereto, as I contemplate changes in form and the proportion of parts and the substitution of equivalents as circumstances may suggest or render expedient without 110 departing from the spirit or scope of my invention.

I claim:

1. Inking mechanism for printing presses comprising in combination an inking fountain, a fountain ink roll mounted on said fountain, an inking plate, a form inking carriage, rocker arms upon which said form inking carriage is mounted, a power-operated distributing roll having a rotary move- 115 120 125 130

ment in each direction, an auxiliary inking carriage adapted to alternately contact with said ink distributing roll and said inking plate, means for carrying ink from said 5 fountain roll to said distributing roll and connections to said rocker arms whereby said distributing roll and said auxiliary carriage are operated.

2. Inking mechanism for printing presses, 10 comprising in combination an inking fountain, fountain ink roll secured thereto, an inking plate, a form inking carriage, rocker arms upon which said form inking carriage is mounted, a power operated ink distributing roll having a rotary movement in each 15 direction and also an axial movement, an auxiliary inking carriage having rollers adapted to alternately contact with said ink distributing roll and said inking plate and 20 gear connection to one of said rocker arms, whereby the said distributing roll and auxiliary inking carriage is operated.

3. Inking mechanism for printing presses, 25 comprising in combination an inking fountain, an ink feeding roller secured to said fountain, a stationary ink plate, a power operated distributing roll, an auxiliary inking carriage having rollers adapted to contact with said ink distributing roll having a 30 backward and forward rotary movement and also an axial movement, and also with said inking plate, a pair of upwardly extending rocker arms, an ink conveying roller mounted upon said rocker arms, a form inking carriage and means upon said rocker arms for engaging the said auxiliary inking carriage whereby the ink conveying roll is alternately brought in contact with said fountain roller and said distributing roller.

40 4. Inking mechanism for printing presses comprising in combination an ink fountain, an inking plate, a fountain roller, a distributing roller, means for conveying ink from said fountain roller onto said distributing roller, 45 an inking plate carriage having rollers thereon adapted to alternately contact with the distributing roller and the said inking plate, a form inking carriage, a pair of rocker arms upon which said form inking carriage is 50 mounted, connecting means between said rocker arms and said inking plate carriage whereby the said inking plate inking carriage is operated, and means for rotating the said ink distributing roller in the same direction 55 as the travel of the said inking plate carriage.

5. Inking mechanism for printing presses comprising in combination an ink fountain, a power-driven fountain roller mounted upon the said fountain, an ink distributing roller, 60 a conveying roller adapted to contact in rolling engagement with said fountain roller and said distributing roller, a plate inking carriage, rollers mounted in said inking carriage, means for mounting said inking carriage upon the printing press, a form inking

carriage, a pair of rocker arms upon which said form inking carriage is mounted, operating connections between said rocker arms and the said inking carriage whereby the latter is actuated, a threaded shaft upon which said ink distributing roller is mounted and a cooperating threaded member carried by said distributing roll in engagement with the threaded portion of said shaft, whereby the said ink distributing roller is given a 75 reciprocatory movement.

6. Inking mechanism for printing presses, 80 comprising in combination an ink fountain, an ink supply roller mounted upon said fountain, form rollers, rocker arms upon which the said form rollers are mounted, an inking plate, a reciprocating distributing roller, means for conveying an ink supply to 85 said distributing roller, an auxiliary ink distributing carriage having rollers adapted to contact with said distributing roller and with said inking plate, racks upon which the said traveling rollers are mounted, a toothed element connected to one of said rocker arms, and gears connecting said distributing roller 90 and said toothed element.

7. Inking mechanism for printing presses, 95 comprising in combination an ink fountain, an ink supply roller mounted upon said fountain, form rollers, rocker arms upon which the said form rollers are mounted, an inking plate, a reciprocating distributing roller, means for conveying an ink supply to 100 said distributing roller, an auxiliary ink distributing carriage having rollers adapted to contact with said distributing roller and with said inking plate, racks upon which the said traveling rollers are mounted, a toothed element connected to one of said rocker arms, gears connecting said distributing roller and 105 said toothed element, a pair of rocking arms, a roller mounted thereon, a cam connected to one of said rocking arms, means on said auxiliary ink distributing carriage for engagement with said cam whereby the roller carried by said rocking arms is moved into contact with said fountain roller, and held in 110 rolling engagement therewith for a predetermined time.

8. An inking mechanism for printing 115 presses, comprising in combination a fountain roller, a distributing roller, an inking carriage having rollers adapted to contact with the said distributing roller and the inking plate of a printing press, form inking rollers, 120 rocker arms upon which said form inking rollers are mounted, a pair of toothed rack bars upon which said inking carriage is mounted, gear wheels carried by said distributing roll and driving said pair of rack bars, 125 a toothed element secured to the form inking roller rocker arms and gear connections between said toothed element and the said distributing roll.

9. An inking mechanism for printing 130

presses, comprising in combination a fountain roller, a distributing roller in operative engagement with a threaded shaft, an inking carriage having rollers adapted to contact 5 with the said distributing roller and the inking plate of a printing press, a pair of toothed rack bars upon which said inking carriage is mounted, gear wheels carried by said distributing roll and driving said pair 10 of rack bars, form inking rollers, rocker arms upon which said form inking rollers are mounted, a toothed element secured to the form inking roller, rocker arms and gear connections between said toothed element and 15 the said distributing roll.

10. An inking mechanism for printing presses, comprising in combination a fountain roller, a distributing roller, an inking carriage having rollers adapted to contact 20 with the said distributing roller and the inking plate of a printing press, a pair of toothed rack bars upon which said inking carriage is mounted, gear wheels carried by said distributing roll and driving said pair of rack 25 bars, form inking rollers, rocker arms upon which said form inking rollers are mounted, a toothed element secured to the form inking roller rocker arms, gear connection between said toothed element and the said distributing 30 roll, and a reciprocating roller adapted to alternately engage said fountain roller and said distributing roller.

11. An inking mechanism for printing presses, comprising in combination a fountain roller, a distributing roller, an inking carriage having rollers adapted to contact 35 with the said distributing roller and the inking plate of a printing press, a pair of toothed rack bars upon which said inking carriage is mounted, gear wheels carried by said distributing roll and driving said pair of rack 40 bars, form inking rollers, rocker arms upon which said form inking rollers are mounted, a toothed element secured to the form inking roller rocker arms, gear connections between said toothed element and the said distributing 45 roll, a cam, a roller on said inking carriage adapted to engage said cam and a pair of rocker arms connected to said cam and a roller 50 mounted upon the ends of said rocker arms, the said roller being held in rolling peripheral contact with the said fountain roller at predetermined times.

12. An inking mechanism for printing 55 presses having an ink supply roll mounted thereon, an ink distributing roller, means for conveying ink from said ink supply roll to said distributing roller, gears mounted upon said ink distributing roller, a pair of racks 60 in engagement with the gears on said distributing roll, an inking carriage having a plurality of rollers adapted to contact with said distributing roller and the inking plate of the press, a segmental gear, an arm connected to said segmental gear and to said 65

fountain roll, form inking rollers, rocker arms upon which said form inking rollers are mounted, and a connecting rod between said arm and one of the rocker arms of the form inking rollers. 70

13. An inking mechanism for printing presses comprising in combination ink supply means, a fountain roller, a distributing roller, form inking rollers, rocker arms upon which said form inking rollers are mounted, 75 a driving rod connected to the rocker arm of the printing press, a segmental gear to which said driving rod is connected, gear mechanism connecting said segmental gear and the distributing roller, an auxiliary inking carriage having rolls adapted to contact with said distributing roller, means whereby the said auxiliary inking carriage travels onto the inking plate of a printing press, and a movable roller adapted to alternately engage 80 in rolling contact with the said fountain roller and the said distributing roller. 85

14. An inking mechanism for printing presses comprising in combination ink supply means, a fountain roller, a distributing 90 roller, form inking rollers, rocker arms upon which said form inking rollers are mounted, a driving rod connected to the rocker arm of the printing press, a segmental gear to which said driving rod is connected, gear 95 mechanism connecting said segmental gear and the distributing roller, means for forcing the rollers of said auxiliary inking carriage out of engagement with said distributing roller and onto the inking plate of the 100 printing press, and a movable roller adapted to alternately engage in rolling contact with the said fountain roller and the said distributing roller.

15. Inking mechanism for printing presses comprising an inking fountain, an inking roll mounted thereon, a form inking carriage, a pair of rocker arms upon which said form inking carriage is mounted, connections between said inking roll and said rocker arms 105 whereby the said inking roll is actuated, an ink distributing roll, a duct roll adapted to alternately engage said inking roll and said distributing roll in rolling contact therewith and being held in normal contact with said distributing roll, an ink plate, an inking carriage having a pair of spaced inking rollers mounted thereon, a pair of toothed rack bars upon which said inking carriage is mounted, 110 gears adapted to operate said inking carriage and said distributing roll, operating connections between said gears and said rocker arms, and means on said inking carriage adapted to move said duct roll out of contact with said distributing roll and into engagement with 115 said fountain ink roll.

16. Inking mechanism for printing presses comprising an inking fountain, an inking roll mounted thereon, a form inking carriage, a pair of rocker arms upon which said form 120

130

inking carriage is mounted, connections between said inking roll and said rocker arms whereby the said inking roll is actuated, an ink distributing roll, a duct roll adapted to alternately engage said inking roll and said distributing roll in rolling contact therewith, and being held in normal contact with said distributing roll, an ink plate, an inking carriage having a pair of spaced inking rollers 10 mounted thereon, a pair of toothed rack bars upon which said inking carriage is mounted, gears adapted to operate said inking carriage and said distributing roll, operating connections between said gears and said rocker arms, 15 and means on said inking carriage adapted to move said duct roll out of contact with said distributing roll and into engagement with said fountain ink roll, one of the said inking rollers being adapted to ride over said distributing roller and both of said rollers being brought into contact with said distributing roller.

17. Inking mechanism for printing presses comprising an inking fountain, an inking roll mounted thereon, a form inking carriage, 20 a pair of rocker arms upon which said form inking carriage is mounted, connections between said inking roll and said rocker arms whereby the said inking roll is actuated, an ink distributing roll, a duct roll adapted to alternately engage said inking roll and said distributing roll in rolling contact therewith, and being held in normal contact with said distributing roll, an ink plate, an inking carriage having a pair of spaced inking rollers 25 mounted thereon, a pair of toothed rack bars upon which said inking carriage is mounted, gears adapted to operate said inking carriage and said distributing roll, operating connections between said gears and said rocker arms, and means on said inking carriage adapted to move said duct roll out of contact with said distributing roll and into engagement with said fountain ink roll, the said 30 distributing roller having a longitudinal movement as well as a rotary movement.

18. Inking mechanism for printing presses comprising in combination an inking fountain, fountain ink roll mounted on said fountain, an inking plate, a form inking carriage, 45 rocker arms upon which said form inking carriage is mounted, a power operated distributing roll, an auxiliary inking carriage having rollers mounted thereon adapted to alternately contact with said ink distributing roll and said inking plate, means for carrying ink from said fountain roll to said distributing roll, a connection to said rocker arms whereby the said distributing roll and 50 said auxiliary carriage are operated, the said auxiliary inking carriage having a plurality of inking rolls each of which is adapted to be brought into contact with the distributing roller.

19. Inking mechanism for printing presses

comprising in combination an inking fountain, fountain ink roll mounted on said fountain, an inking plate, a form inking carriage, 55 rocker arms upon which said form inking carriage is mounted, a power operated distributing roll, an auxiliary inking carriage having ink rolls mounted thereon adapted to alternately contact with said ink distributing roll and said inking plate, means for carrying ink from said fountain roll to said distributing roll, a connection to said rocker arms whereby the said distributing roll and said auxiliary carriage are operated, the said auxiliary inking carriage having a plurality of inking rolls each of which is adapted to be 60 brought into contact with the distributing roller.

20. Inking mechanism for printing presses comprising in combination an inking fountain, fountain ink roll mounted on said fountain, an inking plate, a form inking carriage, 65 rocker arms upon which said form inking carriage is mounted, a power operated distributing roll, an auxiliary inking carriage having ink rolls mounted thereon adapted to alternately contact with said ink distributing roll and said inking plate, means for carrying ink from said fountain roll to said distributing roll, a connection to said rocker arms whereby the said distributing roll and said auxiliary carriage are operated, the said auxiliary inking carriage having a pair of inking rolls each of which is adapted to be 70 brought into contact with the distributing roller.

21. Inking mechanism for printing presses comprising in combination an inking fountain, fountain ink roll mounted on said fountain, an inking plate, a form inking carriage, 75 rocker arms upon which said form inking carriage is mounted, a power operated distributing roll, an auxiliary inking carriage having ink rolls mounted thereon adapted to alternately contact with said ink distributing roll and said inking plate, means for carrying ink from said fountain roll to said distributing roll, a connection to said rocker arms whereby the said distributing roll and said auxiliary carriage are operated, the said auxiliary inking carriage having a pair of inking rolls each of which is adapted to be 80 brought into contact with the distributing roller.

22. Inking mechanism for printing presses comprising in combination an inking fountain, fountain ink roll mounted on said fountain, an inking plate, a form inking carriage, 85 rocker arms upon which said form inking carriage is mounted, a power operated distributing roll, an auxiliary inking carriage having ink rolls mounted thereon adapted to alternately contact with said ink distributing roll and said inking plate, means for carrying ink from said fountain roll to said distributing roll, a connection to said rocker arms whereby the said distributing roll and said auxiliary carriage are operated, the said auxiliary inking carriage having a pair of inking rolls in normal horizontal alignment 90 with each other, each of said rolls being adapted to contact with the distributing roller.

22. Inking mechanism for printing presses comprising in combination an inking fountain, fountain ink roll mounted on said fountain, an inking plate, a form inking carriage, 95 rocker arms upon which said form inking carriage is mounted, a power operated distributing roll, an auxiliary inking carriage having ink rolls mounted thereon adapted to alternately contact with said ink distributing roll and said inking plate, means for carrying ink from said fountain roll to said distributing roll, a connection to said rocker 100 arms whereby the said distributing roll and said auxiliary carriage are operated, the said auxiliary inking carriage having a plurality of inking rolls each of which is adapted to be 105 brought into contact with the distributing roller.

- arms whereby the said distributing roll and said auxiliary carriage are operated, the said auxiliary inking carriage having a pair of inking rolls in normal horizontal alignment with each other, each of said rolls being adapted to contact with the distributing roller, the uppermost of said rolls passing over said distributing roller and contacting therewith after it has passed over said roller.
- 10 23. A plate inking mechanism, comprising in combination, an ink fountain, an ink roller mounted on said fountain, an ink distrib-

uting and conveying roller having a rotary movement in each direction, a duct roller adapted to carry ink from said fountain 15 roller to said distributing and carrying roller, and an ink distributing carriage having a plurality of roller members thereon, each of said rollers being adapted to contact with the surface of the distributing roller and 20 with the surface of the inking plate.

Signed at Chicago, Illinois, this 28 day of June, 1924.

JOHN H. SCHUSSLER.
